[57] CLAIM

The ornamental design for a sole for cast shoe, as shown.

DESCRIPTION

FIG. 1 is a top perspective view of a sole for a cast shoe showing my new design;

FIG. 2 is a bottom perspective view thereof;

FIG. 3 is a top plan view thereof; and

FIG. 4 is a side elevational view thereof.

The broken line showing of the upper portions of a cast shoe and the tread is for illustrative purposes only and forms no part of the claimed design.

FIG. 4
